UNITED STATES PATENT OFFICE.

JAMES N. FURRY, OF LODI, CALIFORNIA.

GRAPE-PACKING CRATE.

1,183,184.

Specification of Letters Patent.

Patented May 16, 1916.

Application filed January 4, 1915. Serial No. 371.

To all whom it may concern:

Be it known that I, JAMES N. FURRY, a citizen of the United States, residing at Lodi, in the county of San Joaquin, State 5 of California, have invented certain new and useful Improvements in Grape-Packaging Crates; and I do declare the following to be a clear, full, and exact description of the same, reference being had to the accompanying drawings, and to the characters of reference marked thereon, which form a part 10 of this application.

This invention relates to improvements in crates used for packing grapes for shipment and sale, the object of the invention being to produce such a crate which, when used for packing grapes, can be used in the field, thus obviating the necessity of handling the grapes a great many times, thus 20 aiding in keeping the bloom on the grapes which results in their keeping much better during shipment.

A further object of the invention is to allow the grapes to be packed in a compact 25 and attractive manner, so that when opened for display purposes they will appear to best advantage.

These objects are carried out by having a removable mold which fits into the crate, 30 such mold being in the form of four bottomless baskets, the grapes being packed carefully into the mold and then the mold being removed and baskets substituted therefor and the crate then nailed up ready for shipment.

In addition to the advantages above noted, by the use of my improved crate, the grapes may be packed much more quickly, cheaply 40 and with less damage to the fruit than by the ordinary means now commonly employed for the purpose.

A still further object of the invention is to produce a simple and inexpensive device and yet one which will be exceedingly effective for the purposes for which it is 45 designed.

These objects I accomplish by means of such structure and relative arrangement of the parts as will fully appear by a perusal 50 of the following specification and claim.

On the drawings, similar characters of reference indicate corresponding parts in the several views.

Figure 1 is a perspective view of a crate 55 showing my improved mold in position

therein. Fig. 2 is a perspective view of a crate packed ready for shipment. Fig. 3 is a top plan view of my improved mold. Fig. 4 is a side elevation of the same.

Referring now more particularly to the characters of reference on the drawings, the numeral 1 designates the crate which is of the usual size and adapted to receive four of the ordinary grape baskets 2 now commonly employed for the packing of grapes. 65 In packing my improved crate 1, I first nail the top 3 onto the same leaving the bottom open. I then insert the mold into the open bottom of the crate, which mold consists of a cross bar 4 adapted to rest on the top 70 edges of the ends of the crate and suspended on which are four forms 5, each being substantially the shape of one of the baskets 2 but having no bottom or top. The grapes are then packed into the forms 5 in the 75 proper quantities and in an artistic and attractive manner.

The forms are provided with inclined or sloping sides from their tops to their bottoms as shown substantially in Fig. 4. The 80 grapes are packed very snugly into the forms and pressed slightly downwardly after they are packed. This tends to mold them into the compact form, the grapes closely adhering one to the other, and by reason of the 85 sloping sides mentioned above, the forms can then be readily slipped off the molded piles of grapes, which will hold their form until the baskets 2 can be fitted over them. When the baskets 2 are fitted over the 90 molded forms of the grapes made by the molds, the bottom of the crate is then nailed into position whereupon the packing operation is completed. In this way the grapes can be packed, as stated, in the field, obviating needless handling of the same over and over, the advantageous results of which can readily be seen. Also the actual weight for each crate can be obtained.

From the foregoing description it will 100 readily be seen that I have produced such a device as substantially fulfills the objects of the invention as set forth herein.

While this specification sets forth in detail the present and preferred construction 105 of the device, still in practice, such deviations from such detail may be resorted to as do not form a departure from the spirit of the invention, as defined by the appended claim.

Having thus described my invention what I claim as new and useful and desire to secure by Letters Patent is:—

A device of the character described comprising the combination with a crate having its top nailed in position, of a cross bar adapted to be removably suspended across the open bottom of the crate, molds suspended on such cross bar and projecting

into the crate, such molds having no tops or bottoms, as described.

In testimony whereof I affix my signature in presence of two witnesses.

JAMES N. FURRY.
